CLAIM

The ornamental design for a footrest strap for a wheelchair, as shown and described.

DESCRIPTION

FIG. 1 is a top, front, and right side axonometric view of a footrest strap for a wheelchair, showing my new design; FIG. 2 is a bottom, front, and left side axonometric view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash lines in the figures illustrate the portions of the footrest strap for a wheelchair that form no part of the claimed design.

1 Claim, 8 Drawing Sheets
